Patented Feb. 2, 1915.

UNITED STATES PATENT OFFICE.

LOUIS N. D. WILLIAMS, OF OGONTZ, PENNSYLVANIA.

TRANSFERRING KNITTED WEBS.

4,127,337.

Specification of Letters Patented Feb. 2, 1915.

Application filed August 6, 1913. Serial No. 733,298.

To all whom it may concern:

Be it known that I, LOUIS N. D. WILLIAMS, a citizen of the United States, residing in Ogontz, Montgomery county, Pennsylvania, have invented certain Improvements in Transferring Knitted Webs, of which the following is a specification.

My invention relates to the transfer of a knitted web from the needles on which it was produced to transfer points or quills (hereinafter, for convenience, termed "quills") whereby the web can be applied to the points of a looping machine, or whereby the stitches may be transferred from one half of the quills to the other half of the same so as to double the stitches on each of the latter half before transferring them to the "points" of a looping machine to be united by a course of stitches, or whereby the double stitches can be united while upon the quills without being transferred to the points of a looping machine.

The object of my invention is to so effect the transfer of the web from the knitting needles to the transfer quills as to insure proper registry of each of the quills with its corresponding stitch of the web, and to prevent undue strain upon the stitches which are thus transferred, thereby, in case of webs of fine gage knitted with light yarn, avoiding the possibility of fracture of any of the stitches or overstraining of the same which will impair the integrity of the joint or seam subsequently formed by uniting the double stitches. This object I attain by applying the transfer quills to stitches of the web preceding those last formed upon the needles, whereby the full stitch opening is available for the reception of the transfer quills, whereas, if the quills were applied to the stitches upon the needles not only would the entrance of the quill into the stitch be more difficult to effect but the stitch would have to be stretched so as to receive both the needle and quill, which abnormal stretching and straining of the stitch is, in many cases, not permissible.

In the accompanying drawings—Figure 1 is a sectional view of sufficient of a knitting machine to illustrate one method of carrying out my invention: Figs. 2 and 2^a are views illustrating other means for effecting the desired result; Fig. 3 is a horizontal section on the line a—a. Fig. 2; Fig. 4 is a view of a piece of fabric after the same has been

removed from the knitting needles by the transfer quills, and Fig. 5 is a similar but smaller view of a piece of fabric prepared with reference to removal from the needles while leaving a section of knitted web upon the latter to serve as a starting course for a new web.

In removing to transfer quills a knitted web produced upon the needles of a knitting machine the customary practice has been to apply said quills directly to the upper portions of the needles and then to cast the stitches from the needles onto the quills, but this method is objectionable, especially in the case of closely knitted fabrics of fine gage, because the stitches fit so snugly to the needle stems that the proper entry of the transfer quills into the stitches is not easy of accomplishment, and because when they do enter the stitches the presence of both a needle and a quill at the same time in each stitch serves to unduly expand the stitches, especially when the latter are being cast off over the closed latches of the needles, the stitches being thereby subjected to such strain as to materially weaken the same or even, in some cases, to fracture the yarn of which they are composed. In carrying out my invention, therefore, I apply the transfer quills to stitches of the web preceding those last formed upon the needles, so that the full area of each stitch is available for the reception of the transfer quill and the entrance of each quill into its appropriate stitch can be effected more readily and with greater certainty than when the quill is applied to a stitch which is also in engagement with a needle, the engagement of the stitches with the quills, moreover, being effected without stretching the same and therefore without any liability to fracture any stitches or impart excessive strain thereto.

Different means may be employed for carrying out my invention, and in the drawing I have shown two of such means as examples, but other and equivalent means may be devised for the purpose by those skilled in the art.

In Figs. 1 and 2, 1 represents part of the needle cylinder of an ordinary circular knitting machine, and 2 part of the cam cylinder or ring surrounding the same. It should be understood, however, that although my invention has been designed especially for

use in connection with circular machines its use is not limited thereto, since it can be adapted in effecting transfer of webs from straight or flat bed machines as well.

5 One of the needles of the machine is represented at 3, such needle being, during the knitting operation, reciprocated in the grooved face of the cylinder by the usual cams of the cam cylinder 2, which should 10 also be provided with means for raising all of the needles to the clearing point, as shown in Fig. 1, when the transfer is to be effected, the needles being then retracted so as to cast their stitches after the engagement 15 of the transfer quills with the stitches of a preceding course, or the stitches upon the needles being released therefrom by other means, such for instance, as the stitch-severing knife shown in my application for 20 patent Serial No. 774,594, filed June 19, 1913.

The quills 4 of the transfer ring are disposed in a circle having the same diameter as the circle of needles of the knitting machine when the latter are in their normal or knitting position, that is to say, with the backs of the needle stems in contact with the bases of the grooves in the needle cylinder, but in order to bring the stitches of 25 a previously formed course into registry with the transfer quills the knitting needles 3 are projected in the grooves of the cylinder, as shown in Fig. 1, so as to draw the upper edge of the knitted web outwardly 30 over the top of the cylinder and thereby bring the stitches of a previously formed course into registry with the grooves in the needle cylinder so that the points of the transfer quills can pass through said stitches 35 over the top of the cylinder and thereby bring the stitches of a previously formed course into registry with the grooves in the needle cylinder so that the points of the transfer quills can pass through said stitches 40 and into the grooves, as shown in Fig. 1. Various means may be adopted for effecting such projection of the needles 3 in the grooves in the cylinder. In the present instance I have shown for this purpose a reciprocating jack 5, disposed behind the needle 3 and having, at the lower end, a butt 6 which is acted upon by a special cam in the cylinder 2 so as to raise and lower said jack, as required, the upper end of the jack 50 having a butt 7 which, during the knitting operation, is contained in a recess 7^a in the cylinder 1, the jack being then in its lowermost or retracted position. When it is desired to project the needle the jack 5 is raised and the upper end of the butt 7 engages with the inclined top 7^b of the recess 7^a, the effect being to thrust the upper end 55 of the jack outwardly and therefore to impart corresponding outward movement to the shank of the needle, thereby causing the needles to assume the outwardly inclined position shown in Fig. 1 and thus draw the upper edge of the knitted web outwardly 60 over the top of the cylinder.

65 Fig. 2 of the drawing illustrates means

for carrying out my invention without displacement of the needles. In this case quills 8 are inserted in the upper end of the cylinder immediately behind each of the needle guiding grooves therein, the back of each of these quills being, by preference, flush with the base of the groove, and said quills being disposed in a relation the reverse of that of the transfer quills 4, as shown in Fig. 3, said quills 8 providing spaces for the reception of the ends of the transfer quills 4 after the latter have been passed through the stitches of a course of the web preceding that upon the needles, as shown in Fig. 2.

In carrying out my invention the transfer quills will usually engage the course of stitches immediately preceding that upon the needles, as shown in Figs. 1 to 4, but in some cases it may be advisable to permit a portion of the web to hang upon the needles so as to provide the equivalent of a setting-up course on the needles and permit immediate resumption of the knitting of a new web upon the latter without feeding 90 the first course of yarn for said new web to naked needles. In such case I engage the transfer quills with a course of the knitted web considerably in advance of the course upon the needles, as shown for instance, in Fig. 5, in which 9 represents the transfer course and 10 the course upon the needles, there being between these two courses a plurality of intervening courses (four in the present instance) numbered respectively 11, 12, 13 and 14, one of which courses, preferably the course 11, is formed with slack stitches which can be severed after the quills have engaged the stitches of course 9 so as to separate that portion of the web which is to be transferred from the portion which is to remain upon the needles, the lengthening or slackening of the stitches in this course serving as a guide for the cutting instrument whereby the severing of the webs 105 is effected.

When reciprocating web holders are used in connection with the needle cylinder of the machine as is now the customary practice the needles may, while the web holders are retracted, be projected so as to raise the stitches above the level of the tops of the web holders and the latter may then be projected so as to support the web while the transfer quills engage the stitches of 120 a course previous to that last formed upon the needles, as shown for instance in Fig. 2.

I claim:

1. The mode herein described of effecting the transfer of a knitted web from the 125 needles upon which it was produced to the quills of a transfer device, said mode consisting in engaging said quills with the stitches of a course preceding that last formed upon the needles, which said last

formed course still remains upon the needles, and then freeing said engaged course from connection with the needles.

2. The mode herein described of effecting the transfer of a knitted web from the needles upon which it was produced to the quills of a transfer device, said mode consisting in engaging said quills with the stitches of a course preceding that last formed upon the needles, while said last formed course still remains upon the needles, and then freeing said engaged course from connection with the needles and leaving one or more courses of stitches still in connection with said needles.

3. The mode herein described of effecting the transfer of a knitted web from the

needles upon which it was produced to the quills of a transfer device, said mode consisting in engaging the transfer quills with the stitches of a course preceding that last formed upon the needles, while said previously formed course of stitches is supported by the needle carrier and while the last formed course still remains upon the needles, and then freeing said previous course from connection with the needles.

In testimony whereof, I have signed my name to this specification, in the presence of two subscribing witnesses.

LOUIS N. D. WILLIAMS.
